UNITED STATES PATENT OFFICE.

NORMAN B. HURD, OF NEW BRITAIN, CONNECTICUT, ASSIGNOR TO THE AMERICAN HARDWARE CORPORATION, OF NEW BRITAIN, CONNECTICUT, A CORPORATION OF CONNECTICUT.

LOCK.

1,169,541.

Specification of Letters Patent. Patented Jan. 25, 1916.

Application filed July 29, 1915. Serial No. 42,468.

To all whom it may concern:

Be it known that I, NORMAN B. HURD, a citizen of the United States of America, residing at New Britain, Hartford county, 5 State of Connecticut, have invented a new and useful Lock, of which the following is a specification.

My invention relates to locks, and consists in providing certain features of improvement hereinafter fully described, the chief object of which is to enable the lock to be rendered ineffective at times. For example, in school buildings, and in many other public places, it is desirable, and even required 15 in many places, that the exit doors shall be entirely free to open while the building is being occupied, say by school children in session, or by audiences attending an entertainment. Since the most common form 20 of door holding device is a spring latch, and since such a device will hold a door closed, even though it does not constitute a dead lock, it is in such cases as above referred to, essential to hold back the spring latch during 25 such period or periods. I am aware, of course, that from a broad standpoint there is no invention in merely providing some device, or some means, for holding a latch back, and furthermore, I am aware that such 30 means have been common for many years, therefore, it should be understood that my present invention merely relates to the special means employed herein, which means, in its preferred form, may also perform 35 other functions, as I shall make apparent.

In the drawings: Figure 1 is a front elevation of a lock constructed to embody my invention. Fig. 2 is a side elevation thereof, with one side of the lock case removed. 40 Fig. 3 is a similar view showing parts in a different position. Fig. 4 is a detail view, partly in section. Fig. 5 is another detail view, also partly in section. Figs. 6 and 7 are perspective views of detached details. 45 Fig. 8 is a side elevation on a reduced scale of a lock operating device.

1 represents the face plate of a lock, through which projects a spring latch bolt 2, and, in this particular instance also, what 50 is termed a controller 3, one side of which is beveled after the manner of a latch, so that it may be repressed by the strike plate (not shown) when the door is being closed, and will be held repressed thereby while the 55 door remains closed.

4 represents a roll-back which may be operated by an inside knob spindle 5.

6 represents a companion roll back which is designed to be operated by an outside knob spindle 7.

8 is a lever pivoted at 9, and which is designed to engage the end 10 of the latch bolt tail 11 for the purpose of retracting the latch. The lever 8 may be swung by turning either of the roll backs 4 or 6, or it may 60 be swung by any other well known means, for example, by means of an arm 12 projecting into a clearance recess 13 in the lower part of the lock case, so as to engage under the lever 8 as shown, whereby when the arm 65 12 is lifted, the latch will be withdrawn. Such devices are common in store door locks and in panic door bolts.

14 is the rotatable key plug of a cylinder lock which carries the usual roll-back 15 75 which is so arranged and associated with the lock that the latch may be retracted from the outside by means of a key independently of the roll-back 6. This operation is effected through the medium of a 80 lever 16 pivoted at 17, one end of the lever engaging the part 10 of the latch, the other end being engageable by the roll back 15.

My present invention relates more par-

ticularly to that part of the apparatus which 85

I am about to describe, and which consists in the novel means for holding the latch bolt retracted whenever desired. This means

comprises a movable dog 18, which in this particular instance, is associated with the 90

roll-back 6 for the outside knob spindle, and which co-operates therewith in such a way that when said roll back is turned to 95

retract the latch as shown in Fig. 3, the dog 18 may be moved into a position to engage 100

said roll back and hold it in said latch re-

tracting position, thereby holding the latch 105

retracted. As shown in Fig. 3, the lever 8 engages the part 10 of the latch bolt indi-

rectly through the end of the lever 16, but 110

this is immaterial. When the outer roll

back stands in the position shown in Fig. 2, the dog 18 may be moved into a notch 19, as shown, thus locking the outer roll

back and spindle 7 so that the door cannot 115

be opened from the outside excepting through the medium of a suitable key, op-

erating through the plug 14. The dog 18 is

operable by key 20, and this key can be em-

ployed for this purpose only when the door 110

is open, since it is insertible through the face plate 1 of the lock. In the preferred construction, I employ a pin cylinder lock which is mounted on the back of the face plate 1, and is provided with the usual plug 21 which has the usual key-way, shown in Fig. 1. The dog 18, in its preferred form, is mounted to oscillate concentrically with the plug 21, but is not rigidly secured there-
to. The end of the plug 21 is provided with a shoulder 22, which is arranged to strike against a shoulder 23 on the dog 18, so as to swing said dog into or out of position to engage the roll back 6, thus, the one in charge of a building equipped with such lock on its exit doors, may have it within his power to put the lock in such condition that it cannot be operated from the outside save by a key; or he may put the lock in such condition that it will leave the door free to swing open.

What I claim is:

1. In a lock, a case, a face plate, a spring latch projecting through said face plate, means including a roll-back for manually retracting the latch from one side of said case, and means operable by a key for engaging and disengaging said roll-back, said key operable means having a key-way opening through said face plate.

2. In a lock, a case, a face plate, a spring latch projecting through said face plate, means including a roll-back for manually retracting the latch from one side of said case, and a key operable means for engaging and disengaging said roll-back, said key operable means having a key-way opening through said face plate, said blocking means coöoperating with said roll-back to block it in a plurality of positions.

3. In a lock, a case, a face plate, a spring latch projecting through said face plate, means including a roll-back for manually retracting the latch from one side of said case, and means operable by a key for engaging and disengaging said roll-back, said

key operable means having a key-way opening through said face plate, said key-operable means comprising a rotatable cylinder lock plug.

4. In a lock, a case, a face plate, lock mechanism within the case, rotatable means arranged to coöperate with said lock mechanism to lock and unlock the same, said means being key-operable in both directions and having a key-way opening through said face plate.

5. In a lock, a case, a face plate, a spring latch projecting through said face plate, means including two independently operable roll-backs for manually retracting said latch from either side of said case, and means arranged within the case and operable by a key to engage and disengage one of said roll-backs, said key operable means having a key-way opening through said face plate.

6. In a lock, a case, a face plate, a spring latch projecting through said face plate, two manually operable independent means for retracting said latch from the out-door side of the case, and a separate means for retracting said latch from the in-door side of the case, a key-operable blocking device operating to prevent the retraction of the latch by one of the said independent means, said key-operable device having a key-way opening through said face plate, said key-operable device also coöoperating with said latch retracting means to hold the latch bolt retracted.

7. In a lock, a case, a face plate, a bolt, bolt operating mechanism within the case, a rotatable key-operable controlling means arranged to coöperate with the said operating mechanism within the case to lock and unlock the same by the action of a key, and having a key-way opening through said face plate, and means to operate said bolt independently of the aforesaid operating mechanism when the latter is locked by said key.

NORMAN B. HURD.
